CONTROL STATION FOR PROCESS CONTROLLER

Roger B. Kerr, Topsfield, Mass., assignor to General
Electric Company, a corporation of New York

Filed June 20, 1963, Ser. No. 75,443

Term of patent 14 years

(Cl. D26—1)

FIG.1

Des. 198,684

PAGE 2

FIG.2

FIG. 3

FIG. 1 is a perspective view of a control station for process controller showing one form of my design wherein the front panel comprises two arcuate edgewise indicators, an interposed circular dial, and a generally circular mode control switch;

FIG. 2 is a perspective view of a control station for process controller showing another form of my design wherein the front panel comprises two arcuate edgewise indicators and a generally circular mode control switch which is located below the lower one of the two indicators;

FIG. 3 is a perspective view of a control station for process controller showing yet another form of my design wherein the front panel comprises two arcuate edgewise indicators and a circular control dial interposed between the indicators.

The essential features of my design reside in the portion shown in solid lines.

The generic feature of my design common to the three illustrated forms is attributable to the spatial interrelation-

ship between the arcuate indicators and generally circular control element, as well as their manner of cooperation with the planar face of the supporting panel.

I claim:

The ornamental design for a control station for process controller, as shown and described.
